ABSTRACT

A *Chrysanthemum* plant named 'Zanmumajes' characterized by its small sized blooms with purple ray florets and prolific branching; natural season flowering date September 23-27 (week 39); blooming for a period of 4 weeks.

3 Drawing Sheets

1

Botanical designation: *Chrysanthemum×morifolium* Ramat.
Cultivar denomination: 'Zanmumajes'.

BACKGROUND OF THE INVENTION

The present invention relates to a new and distinct cultivar of *Chrysanthemum* plant, botanically known as *Chrysanthemum×morifolium* Ramat., commercially known as a garden mum, and hereinafter referred to by the cultivar denomination 'Zanmumajes'. 'Zanmumajes' is a product of a breeding and selection program for outdoor pot mums (garden mums) which had the objective of creating new cultivars with a double type inflorescence, a natural season flowering date around week 39, blooming for a period of 5 weeks. 'Zanmumajes' is a seedling resulting from a cross of the female parent id 28184 (not patented) with the male parent id 26513 (not patented). Plants of the new cultivar 'Zanmumajes' differ from its parent in inflorescence color; the inflorescences of the seedling are purple with a dark center, while they are two-tone pink in the female parent and dark pink in the male parent.

The new and distinct cultivar was discovered and selected as a flowering plant by Henricus Cornelius Maria Jacobs on a cultivated field in Rijsenhout, The Netherlands in 2005. The first act of asexual production of 'Zanmumajes' was accomplished when vegetative cuttings from the initial selection in 2005 were propagated further in a controlled environment in Rijsenhout, The Netherlands. In summer, about 6-8 days are needed to initiate roots in cuttings of the new cultivar, after another 5 days rooted plants are formed. The new cultivar has been found to retain its distinctive characteristics through successive propagations.

BRIEF DESCRIPTION OF THE DRAWINGS

The present invention of a new and distinct variety of *Chrysanthemum* (of about 18 weeks) is shown in the accom-

2

panying drawings, the color being as nearly true as possible with color photographs of this type.

FIG. 1 shows a plant of the cultivar in full bloom.

FIG. 2 shows the various stages of bloom of the new cultivar.

FIG. 3 shows the various stages of foliage of the new cultivar.

DESCRIPTION OF THE INVENTION

The observations and measurements were gathered from plants, in the period of 17 to 24 weeks of age, grown outdoor in Rijsenhout, The Netherlands, under natural day length and temperature and planted in week 23 in 2013 (with a warm summer), receiving drip irrigation. The natural blooming date of this crop was September 23-27 (week 39). The average height of the plants was 40 cm. No growth retardants were used. No tests were done on disease or insect resistance or susceptibility. No tests were done on cold or drought tolerance. This new variety produces small sized blooms with purple ray florets blooming for a period of 5 weeks. From the cultivars known to the inventor the most similar existing cultivar in comparison to 'Zanmumajes' is 'Venus' (U.S. Plant Pat. No. 14,378). When 'Venus' and 'Zanmumajes' are being compared the following differences are noticed (1). Inflorescence size. And (2). Natural season flower date. (1). Inflorescences of 'Venus' are larger than those of 'Zanmumajes'. (2). Plants of 'Venus' flower earlier in the season than those of 'Zanmumajes'.

The following is a description of the plant and characteristics that distinguish 'Zanmumajes' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum × morifolium</i> Ramat. 'Zannumajes'	
<u>Bud</u>	
Size:	Small; cross-section 3 mm, height 3 mm
Shape:	Round
Texture:	Pubescent
Outside color:	Greyed-green 191A
Phyllaries	
Number:	18, arranged in 3 rows
Shape:	Elliptic
Apex:	Acute
Base:	Truncate
Margin:	Entire
Color:	Upper side: Green 137C Lower side: Yellow-green 144C
Length and width:	3 mm; 1.5 mm
Texture:	Pubescent
Inflorescences	
Type:	Double
Height:	1 cm
Diameter:	3 cm
Peduncle length:	5.5-6.5cm
Peduncle color:	Green 143C
Peduncle diameter:	1.5 mm
Peduncle texture:	Pubescent
Peduncle strength:	Weak
Number per branch:	About 7-8 inflorescences
Duration of flowering:	4 weeks
Seeds:	Produced in small quantities, ovate, Greyed-brown 199A, length 1.5 mm, diameter 0.5 mm; texture: rough with ribs
Fragrance:	Faint chrysanthemum odor
Color inflorescences	
Center of inflorescence:	Immature stage: Greyed-purple 187B; Mature stage: Greyed-purple 187B
Color of upper side of ray florets:	Purple N77B
Color of lower side of ray florets:	Greyed Purple 186C
Tonality from distance:	A garden mum with small decorative purple blooms and a dark center
Color of ray florets after aging of the plant:	Greyed-purple 186C
Ray florets	
Type:	Ligulate
Texture:	Upper and lower side smooth
Number:	90-100
Shape:	elliptic
Apex:	pointed
Base:	attenuate
Cross-section:	flat
Longitudinal axis:	straight
Length of corolla tube:	2 mm
Diameter corolla tube:	0.8-1 mm
Ray floret margin:	Entire
Ray floret length:	1-1.5 cm
Ray floret width:	2-4 mm
Ratio length/width:	Medium
Disc florets	Absent
Receptacle	
Color:	Yellow-green 145D
Shape:	Domed raised
Height:	3 mm
Diameter:	2 mm
Reproductive Organs	
Androecium:	absent
Pollen:	absent
Gynoecium:	Present on ray florets
Style color:	Yellow-green 154C
Style length:	4 mm

TABLE 1-continued

Botanical Description of <i>Chrysanthemum × morifolium</i> Ramat. 'Zannumajes'	
5	Stigma color: Yellow 7A Stigma width: 1 mm Ovary: Enclosed in calyx; color: Yellow-green 149D
	<u>Plant</u>
10	Type: Bushy Growth habit: Spherical shape Growth rate: Medium/Low Height: 40 cm Width: 50 cm Stem color: Greyed-brown 199A Stem strength: weak Stem brittleness: brittle Stem anthocyanin coloration: absent Internode length: 2-3 cm Length of lateral branch: From top to bottom 20-22 cm Lateral branch color: Green 138B Lateral branch, attachment: Weak Lateral branch diameter: 2 mm Lateral branch texture: Pubescent with ribs Branching (average number of lateral branches): Dense with 9 breaks after pinching
15	Natural season blooming date: September 23-27 (week 39) in Rijenhout, The Netherlands.
20	Roots - habits: Fine, freely branching Roots - color: White 155D
25	Foliage
	Glossiness: Leaf upper side: very weak Leaf lower side: very weak 30 Leaf color: Upper side: Green 138A Lower side: Green 139C Color midvein: Upper side: Yellow-green 147D Lower side: Yellow-green 148D Size: Small; length 2.5-4.5 cm, width 1.2-2.4 cm
35	Quantity (number per lateral branches): 20-22 Shape: Elliptic Texture upper side: Sparsely pubescent Texture under side: Pubescent Venation arrangement: Palmate Shape of margin: Serrated
40	Shape of base of sinus between lateral lobes: Rounded Margin of sinus between lateral lobes: Diverging Shape of base: Acute to truncate Apex: Mucronulate 45 Petiole attitude: Moderately upwards Petiole length: 0.2-0.5 cm Petiole diameter: 1.5 mm Petiole color: Yellow-green 147D Stipule: Very small, about 8 mm.
50	

TABLE 2

Differences with the comparison variety, when grown under identical conditions		
	'Zannumajes'	'Venus'
55	Inflorescence size 3 cm Natural season flower date week 35	5-5.5 cm week 39

I claim:

1. A new and distinct *Chrysanthemum* plant named 'Zannumajes' as described and illustrated.
